(57) **CLAIM**

The ornamental design for an automobile tire, as shown and described.

DESCRIPTION

FIG. 1 is a front view of the automobile tire, showing the new design, the rear view, the top plan view and the bottom plan view appearing the same as the front view; FIG. 2 is a right side view of the automobile tire, the left side view appearing the same as the right side view; FIG. 3 is a fragmentary front view, showing in enlargement the portion III—III in FIG. 1;

FIG. 4 is a sectional view, taken on line IV—IV in FIG. 3; and,

FIG. 5 is a same fragmentary front view as FIG. 3 but showing the grooves in the automobile tire in thick lines for clarity of disclosure.
